UNITED STATES PATENT OFFICE

BENJAMIN Z. McCAIN, OF OAK PARK, AND HERBERT L. THOMPSON, OF ELGIN, ILLINOIS,
ASSIGNORS TO ADDRESSOGRAPH COMPANY, OF WILMINGTON, DELAWARE, A COR-
PORATION OF DELAWARE

PRINTING DEVICE

Application filed February 6, 1928. Serial No. 252,148.

This invention relates to printing devices of that class which are adapted to be stored in upright position in a tray or drawer, or stacked in a pile, and run through an address-
5 ing or other printing machine for taking im-
pressions therefrom.

The object of the invention is to provide a printing device having a large information card which may be readily engaged with or
10 disengaged from the printing plate and which will not interfere with the travel of the device through the printing machine.

And another object is to provide a strong and stiff information card of large area but
15 light in weight, having flexible means for engaging it with the printing plate, and which will not increase the thickness of the printing plate.

In the accompanying drawings we have
20 shown a selected embodiment of the invention in which:

Fig. 1 is a front elevation of the printing device.

Fig. 2 is a rear elevation of the printing device.

Fig. 3 is a sectional view on the line 3—3 of Fig. 2.

Referring to the drawings, 4 is the printing plate which is made of metal suitable to permit printing characters 5 to be embossed thereon. The plate is provided on its back with a bead 6 at its lower edge and with flanges 7 at its side edges which serve to stiffen and strengthen the plate, to space
30 plates when stored in a tray or a stack to protect the face of the type characters and to form retainer means for the arms of the card frame. The lower end of each flange is bent to form an end wall 8. Each end of the plate
35 is cut out at 9 through the flange. The upper edge of the plate is cut and bent to form lips 10 of suitable length, one of which, as the middle one, may be offset slightly relatively to the others.

40 The card 11 is made of paper or light cardboard and it is mounted on a light frame 12 preferably made of wire and having flexible arms 13 projecting below the card and terminating in outwardly directed hooks 14.

50 The top and side edges 15 of the card are fold-

ed over the frame and glued or otherwise af-
fixed to the frame. We prefer to make the
frame of light gauge flexible wire doubled
with the parts arranged side by side, as
shown, to provide desired strength and rigid-
ity and to avoid making the card and frame
bulky.

The card may be readily engaged with the
plate by squeezing the arms and engaging
them with the flanges, after which the card
is pushed down until the lower edge thereof
engages the lips 10 and the hooks 14 engage
the end walls 8. Thus the card is locked to
the plate by the hooks and held in rigid po-
sition projecting in the plane of the plate
from the top thereof by the frame, the re-
tainer flanges and the lips. The folded edges
of the card are not thicker than the beaded
lower edge or the flanged side edges of the
plate so that the addition of the card does
not increase the thickness of the printing
device as a whole.

The card may be made of any desired size
suitable for the purpose and it enables a rec-
ord to be kept of a great deal of information
suitable for many different kinds of business.
For classification purposes and ready refer-
ence an impression of the printing plate form
may be made at the top of the card. The card
may be easily disengaged from the plate for
transfer to another plate, for replacement, or
for any other purpose by squeezing the arms
at the cut outs 9 and then separating the card
from the plate.

We have shown the invention in a simple
form suitable for the purposes intended but
we reserve the right to make any changes
therein in the form, construction and ar-
rangement of parts within the scope of the
following claims:

We claim:

1. The combination of a printing plate
having retainer means at the side edges there-
of, a frame having flexible arms adapted to
be detachably engaged with said retainer
means, and a card carried by said frame.

2. The combination of a printing plate
having retainer means at its side edges, a
card, and a frame engaged with the card and
adapted to be detachably engaged with said

retainer means to support the card on the plate and projecting from the top of the plate.

3. The combination of a printing plate
5 having retainer means at its side edges, a
card, and a wire frame engaged with the
card and having arms to engage said retainer
means.

4. The combination of a printing plate
10 having retainer means at its side edges, a
card, and a doubled wire frame engaged with
the card and having arms to engage said retainer
means.

5. The combination of a printing plate having
15 retainer means at its side edges, a card,
and a wire frame engaged with the top and
side margins of the card and having arms to
engage said retainer means.

6. The combination of a printing plate
20 having retainer means at its side edges, a
card, a frame engaged with said card and
having flexible arms to engage said retainer
means, and hooks on the ends of said arms.

7. The combination of a printing plate
25 having retainer means at its side edges, a
card, a frame engaged with said card and
having flexible arms to engage said retainer
means, and hooks on the ends of said arms,
said plate being cut out at its side margins

30 to permit the arms to be squeezed for disengaging
the hooks from the retainer means.

8. The combination of a printing plate
having retainer means thereon, a card, a
frame engaged with the card and adapted to
35 engage said retainer means, and lips on the
top edge of the plate to receive the lower
edge of the card.

9. The combination of a printing plate
having retaining means thereon, a frame, a
40 card having its top and side margins folded
over and affixed to the frame, and arms pro-
jecting from the bottom of the frame to en-
gage said retaining means.

10. A printing device comprising a card,
45 arms on the card projecting from one edge
thereof, and a printing plate having retain-
ing means to receive said arms for detachably
connecting the card and plate.

11. A printing device comprising a card
50 member and a printing plate member, one of
said members having arms projecting from
one edge thereof and the other member hav-
ing retaining means to receive said arms for
detachably connecting the members.

55 12. A printing device comprising a card
member and a printing plate member, arms
on one of said members projecting from one
edge thereof, and retaining means on the other
member adapted to receive said arms for de-
60 tachably connecting the members with their
opposing edges in abutting relation and their
front faces in substantially the same plane.
